UNITED STATES PATENT OFFICE

CLARENCE A. BODDIE, OF PITTSBURGH, PENNSYLVANIA, ASSIGNOR TO WESTINGHOUSE ELECTRIC & MANUFACTURING COMPANY, A CORPORATION OF PENNSYLVANIA

CARRIER-WAVE TELEPHONY OVER POWER LINES

Application filed October 24, 1923. Serial No. 670,511.

This invention relates to communication by carrier-wave oscillations, either through space or along wires.

It is an object of this invention to use the same sending and receiving apparatus both for communication and for the control of distant electro-mechanical devices, particularly for the control of distant station-selective means.

10 It is well known that radio-frequency oscillations may be modulated by superposing thereon a periodic change of amplitude. The radio-frequency thus modulated is often called the carrier wave and the modulation is frequently of audio frequency, for carrying telephone messages. Double modulation, by which the carrier wave is made to convey two telephone messages at once, is also known. Control of electro-mechanical devices requires 20 the changes in the radiant energy to endure for periods corresponding to the time required by the electro-mechanical device to respond to the changes. These relatively slow changes will be herein called impulses.

25 If such impulses are produced by intermittent sending and interruption of the carrier wave itself, the result is unsatisfactory because, even when a large amplification is used at radio frequency, there will not be current 30 changes in the output circuit of the detecting device, large enough to make it feasible to control a relay by the radio-frequency energy, and amplification at audio frequency cannot be had when no modulation having 35 audio frequency is present.

It is an object of this invention to overcome this difficulty and control electro-mechanical devices by radiated energy. If a modulation having audio frequency is imposed upon a radio-frequency carrier wave, the detector which receives this energy will give out an audio-frequency current. If such an audio-frequency current is passed through a second detector, the output from the second 40 detector can be used to control a relay. If 45 amplification is needed, it can be performed at audio frequency and consequently there is no difficulty in obtaining in the output circuit, current changes of the size needed by 50 the relay. This principle is employed to ac-

complish the object of this invention just stated.

The audio-frequency modulation is superposed upon the carrier wave, in impulses so that the first detector produces a succession of 55 trains of audio-frequency oscillations. The length of each train corresponds to the time during which the audio-frequency modulations are impressed upon the carrier wave, that is, to the length of one impulse. Such 60 a train produces in the output of the second detector a succession of direct current impulses, each impulse enduring as long as the corresponding impulse of audio-frequency 65 modulation of the carrier wave, which is as long as the corresponding train of oscillations in the output of the first detector.

It is an object of this invention to make use of the method just explained for controlling station selectors or other distant electro-mechanical devices over a system of sending and receiving apparatus that is also used 70 for telephony.

As an incidental object, this invention produces a thermionic device with a changeable 75 set of connections, so that it may serve alternately as a generator of audio-frequency currents and as an amplifier for voice signals.

It is a further object of this invention to produce a system of communication including 80 a dispatcher's station and a number of other stations, in which the dispatcher's station may communicate at any time with any of the other stations, except one that is then engaged in conversation. This object of the 85 invention is accomplished by means of provisions at each station, except the dispatcher's station, for changing the fundamental carrier-wave frequencies at each of said stations.

Otherwise stated, this object of the invention includes so selecting the frequency for sending and the frequency for receiving, at each of the several stations, that any one station may readily place itself in that relation to the other stations which normally is characteristic of the dispatcher's station.

Other objects and constructional details of the invention will be apparent from the following description and claims when read in 100

connection with the accompanying drawings, wherein

Figure 1 is a diagrammatic representation of circuits and apparatus used at one station 5 for sending.

Fig. 2 is a similar illustration for the receiving apparatus at the same station.

Fig. 3 is a diagrammatic representation of the manner in which the several stations are 10 connected into a sending system, and

Fig. 4 is a set of curves illustrating the wave forms employed.

Referring to Fig. 1, the apparatus for sending includes an antenna circuit 1 of the usual 15 form. A coupling 2 is provided between this circuit and a pair of vacuum devices 3 and 4 which have the well known system of connections for the so-called "Heising" or "constant current" production of modulated high 20 frequency. No difference between the usual and familiar construction of these devices and the construction employed in my invention is necessary, but I have found it convenient to employ a source of alternating 25 current 5 instead of a battery for the power for these tubes. A transformer 6 enables this source to supply low potential alternating current for heating the filaments, and a rectifier 7 enables it to supply high potential direct 30 current for the plate circuits. When the sending apparatus is idle, the source 5 is disengaged, but when the sending apparatus is being used, the source is connected thereto by the action of a relay, as will be explained 35 below.

The grid circuit of the modulator tube 4 is coupled by an audio-frequency transformer 8 to the plate circuit of a vacuum tube 9. This tube is also energized from the source 10 5 in the same way as the other tubes. It is capable of two functions depending upon the position of the armature of the relay 11. When this armature is against its back stop, the grid circuit of the tube 9 is connected to 5 the secondary of the transformer 12. This circuit includes a grid biasing battery and goes to the filament through the divided resistor 10. When the armature is against its front contacts, the grid is connected to the 10 coil 13 which is coupled with the plate circuit. From this coil, the grid connection passes through the same biasing battery to the filament. A condenser 14 is in shunt with the coil 12, and the coil 13 and the condenser 14 together 15 form a circuit capable of oscillating at audio frequency. When the relay 11 is energized, therefore, the tube 9 acts as a generator of audio-frequency currents which control the modulator tube 4 and thus produces an audio-frequency 20 modulation of the radio-frequency output from the tube 3. This output passes through the coupling 2 to the antenna 1. If, therefore, the relay 11 is intermittently energized while the sending apparatus is working, the radiations from the antenna 1 will

consist of the radio-frequency carrier wave which is intermittently modulated by impulses of audio frequency.

When the relay 11 is de-energized and the grid circuit of the tube 9 includes the secondary 70 12, voice signals may be impressed upon the grid by means of the telephone transmitter 16, provided that the armature of the relay 17 is against its front stop. The provisions for controlling this relay 17 will be 75 explained below. While the potential of the grid of the tube 9 is controlled by the voice currents, the modulator tube 4 will be correspondingly influenced and the output from the antenna 1 will consist of the radio-frequency carrier wave modulated to correspond 80 to the voice signals.

The receiving apparatus shown in Fig. 2 includes an antenna 21 with the usual circuit connecting it to the ground. The coupling 22 associates this antenna with the first detector tube 23. The connection to the grid of this tube includes a grid condenser 20 and a grid leak 30. The size of this condenser and leak are selected so that the first 85 detector tube 23 will produce, in its output circuit, an audio-frequency current when the receiving energy is modulated by audio frequency, and a voice-signal current when the carrier wave is modulated by the voice signal. 90 This output circuit is coupled by an audio-frequency transformer 24 to an amplifier 25. The output circuit of this amplifier is controlled by the contacts of the relay 26. When the armature of this relay is against its back stop, the output circuit of the amplifier 25 goes through the primary of an audio-frequency transformer 27. The secondary of this transformer leads to the grid of the second detector tube 28. The connection to this 95 grid includes a grid condenser 29 and a grid leak 31. The size of this condenser and leak are so chosen that the second detector tube 28 is capable of rectifying the audio-frequency current which it receives. The plate circuit of the second detector tube 28 includes a relay 32. When the normal current is flowing in this plate circuit, the armature of this relay is held away from its back stop but, when audio-frequency current arrives at the transformer 27 so that the current in the plate circuit of the tube 28 is diminished, the relay 32 releases its armature and establishes a connection at the back stop. Obviously, this requires that this negative impulse in the relay 32, and the impulse of audio-frequency oscillations in the output circuit of the first detector tube 23, shall endure long enough to permit the relay 32 to release. The time of this impulse, while short compared with a whole second, is very long compared with the period of radio frequency and fairly long compared with the period of audio-frequency. It will be evident that with a very sensitive 100 relay this impulse may be very brief.

The output circuit of the amplifier tube 25, when the armature of the relay 26 is against its front stop, includes the primary of an audio-frequency transformer 33, the secondary of which is connected, by conductors 34 and 35 to the telephone receiver 36 in Fig. 1. When the energy received upon the antenna 21 consists of the carrier wave, modulated by the voice signal, the first detector tube 23 will produce in its output circuit an audio-frequency current whose amplitude varies in accordance with the voice signal. This current will be amplified by the tube 25 and will produce voice signal currents in the transformer 33 so that the voice signal will be reproduced in the receiver 36.

Between the coupling 2 for the antenna 1, in Fig. 1, and the antenna 21, in Fig. 2, there is connected a tuned circuit which is described at greater length in my co-pending application, Serial No. 658,041, filed August 18, 1923, which has since matured into Patent No. 1,673,548. The purpose of this connection between the sending and receiving antenna is to prevent the energy radiated by the antenna 1 from affecting the receiving apparatus in its own station. The connection includes two conductors 40 and 37 which are united to the coupling coil 2 at points on opposite sides of the ground connection 38. On Fig. 2 it may be seen that the conductor 40 includes an adjustable resistor 39 and the conductor 37 an adjustable condenser 41. The conductors 40 and 37 are united together and to the antenna 21 as shown at 42.

When the operation of the system requires that the sending and receiving antennæ have their constants changed, to establish communication with a selected station, the change at the sending station, is accomplished by the triple pole, double throw switch 43, Fig. 1, which is controlled by the relay 44, as will be explained below. When this switch is in the illustrated position, a certain portion of the inductance in the coupling 2 is included in the antenna circuit. When the switch is in the opposite position a smaller portion of the inductance 2 is included in the antenna circuit. The changes in the circuit of the antenna 21, in Fig. 2, are effected by a relay 45. When the armature of this relay is against its front stop, the supplementary condenser 46 is included in the antenna circuit in parallel with the usual tuning condenser. A similar change in the oscillating circuit associated with the coupling 22 is effected by the relay 47. When the armature of this relay is against its front stop, the condenser 48 is connected in parallel to the condenser permanently in this oscillating circuit. When these changes are made, a corresponding change is needed in the connection between the two antennæ afforded by the conductors 36 and 37. This is effected by the relay 49. When the armature of this relay is against its front con-

tact, the condenser 51 is connected in parallel to the condenser 41, already described.

The connections and arrangement of the several relays will be best explained in connection with a description of the operation of the system. This will first be given for two stations each equipped with the apparatus illustrated in Fig. 1 and Fig. 2 and the application to a system embodying more than two stations will be explained afterward.

Assume that all the parts are in the position illustrated in the drawings and that the operator at one station, hereinafter designated as the calling station, wishes to communicate with a certain station hereinafter named the called station. He first removes the telephone receiver 36 from its hook. This establishes a connection through the relay 53, from the battery 54, over the conductors 55, 56 and 57 to the ground. The energization of the relay 53 closes a circuit from the source 5 through the relay 58. Energization of the relay 58 starts the transformer 6 and rectifier 7, so that the filaments are heated and the plate circuits energized throughout the whole of the sending apparatus.

Removing the receiver 36 from its hook also establishes a connection from the battery 59, through the relay 17, conductors 56 and 57 to ground so that the relay 17 picks up and establishes a connection from the battery 61, through the primary of the transformer 12, conductor 62, through the telephone transmitter 16 and conductor 57 to ground. This places the telephone transmitter into condition for delivering voice currents whereby the sending apparatus is now ready for voice signalling.

If the choice of the station with which the operator is to communicate requires that the constants of his antenna be changed, the operator will correspondingly manipulate the dial 63. This dial opens and closes the circuit a predetermined number of times, depending upon the manner in which the operator manipulates it. For changing the constants of the antenna, the operator causes the dial to close the circuit a number of times which does not correspond to the call for any station. In many systems, the dial closes the circuit from one to nine times for each digit in the call number of the desired station, leaving the digit zero, which corresponds to closing the circuit ten times, for any special purpose. Assuming, therefore, that this method is used in the present case, the operator causes the dial 63 to close the circuit ten times. This results in the magnet 64 being energized ten times from the battery 65 over conductors 66 and 67. The ratchet wheel controlled by the magnet 64 is thus rotated through ten spaces which causes contact to be made between the arm 68 and the terminal 69 and thus establishes a circuit from the battery 65, over conductor 71, arm 68, terminal 69 and

115

120

125

130

conductor 72 to the relay 73. Energizing the latter relay causes the relay 44 to pick up, because this relay is energized from the source 5 over conductors 74.

The selector, including magnet 64 and the mechanism operated thereby, is shown only diagrammatically because its details form no part of the invention covered by this application. As is well known to those skilled in the automatic telephone art, after the operation of the dial 63 has closed the circuit a predetermined number of times, the cessation of impulses from the dial permits the ratchet wheel and its arm to return to their normal position. The relay 44 closes a shunt about the contacts of relay 73 and so remains energized after arm 68 and terminal 69 have separated. The relay 44, by closing the switch 75 establishes a circuit from the battery 76 over conductors 78 and 79 to relays 45, 47 and 49 in Fig. 2. The energization of the relays 45, 47 and 49 connects the condensers 46, 48 and 51 so that they add their capacities to the several circuits as already described.

It will be obvious that the connection between battery 65 and conductor 72 could be established by a supplementary circuit closer instead of by a special manipulation of the dial 63, if desired. It will also be obvious that instead of controlling the changes in the antenna 21 and its associated circuits by the relay 44, a key or dial forming part of the receiving apparatus may be provided for this purpose. It will also be obvious that the closing of the contact between arm 68 and terminal 69 may be performed by the operator either before or after the telephone receiver 36 is removed from its hook.

After the receiver is removed from its hook, the operator can establish communication with a selected station by sending, by means of the dial 63, the requisite number of impulses. Each time that the dial 63 closes the circuit, the relay 11 is energized from the battery 81 over conductors 82, 66 and 67 to ground. This causes the vacuum tube 9 to generate audio-frequency trains. The number and duration of these trains correspond to the number and duration of the impulses sent out by the dial 63. As explained above, this operation of the tube 9 causes the carrier wave to be intermittently modulated, the modulations being of audio frequency and their duration constituting the impulses.

When this radiation is received at the called station, a corresponding current is produced in the antenna 21 at that station. This gives, in the output circuit of the first detector tube 23 there, a series of trains of audio-frequency oscillations, which are amplified by the tube 25 and produce in the second detector, a series of diminutions, or negative impulses, in its output current. Consequently, the relay 32, at the called station, closes each time that dial 63 closes its circuit at the call-

ing station, and the duration of the closure of the relay 32 corresponds to the duration of the impulses from the dial.

Each time that the contacts of relay 32 close, a circuit is established from the conductor 79 over conductor 83 through the magnet 84 to the battery 85, returning over conductor 79. Thus the magnet 84, at the called station, is energized each time that the dial 63 at the calling station closes the circuit. This operates the ratchet wheel 85^a and causes contact between the terminal 86 and the arm 87, when the requisite number of impulses have been sent. Stations, other than the called station, will have their contacts corresponding to 86 and 87 closed either by a smaller or a larger number of impulses. If the closure at said other station corresponds to a smaller number of impulses, it will not produce any result, because it does not last long enough. If the closure at the other station corresponds to a larger number of impulses, it does not occur when the dial is manipulated for calling the desired station. When the proper number of impulses has been sent and the arm 87 contacts with the terminal 86, it remains there until the release mechanism responds to the cessation of the impulses, and permits the ratchet wheel 85^a to return to its normal position. The mechanism by which this is accomplished is familiar to those skilled in the art of automatic telephony and does not need to be described here.

The circuit established by the arm 87 is through conductor 88, the magnets 89 and 91 in parallel, and conductor 92 to the battery 59. It should be noticed that this circuit is not open at the relay 17, because it is the relay 17 at the calling station which is energized and the circuit just traced is at the called station. The energization of the relay 91 establishes a holding circuit for it and the relay 89. This circuit extends from the ground at 93 through the relays 91 and 89 in parallel and conductor 92 as before described. The energization of the relay 89 closes a circuit from the battery 94 over conductor 95 to the bell 96 and to ground. This causes the bell to ring and to continue to ring until the operator at the called station removes the receiver 36, thus energizing the relay 17 at the called station and opening the connection between conductor 92 and battery 59. The energization of the relay 17 at the called station connects its telephone transmitter 16 to the transformer 12 and battery 61.

Lifting the receiver 36 also closes a connection from the ground through conductor 57, switch hook, conductor 97, and relay 26 to the battery 98. Energizing the relay 26 changes the connections of the amplifier tube 25 whereby, instead of the primary of the transformer 27, the primary of the transformer 33 is in its output circuit. It will

be impossible for any other station to call the called station while the receiver 36 is off of its hook, because no energy can be transmitted from the amplifier 25 to the second detector

5 28. Including the primary of the transformer 33 in the output circuit of the amplifier 25 couples this output circuit to the telephone receiver 36 so that conversation is now possible between the calling and the called station.

10 Referring to Fig. 4, the manner in which the impulses sent out by the dial 63 are translated into motions of the armature of the relay 32 will become clearer. The curve A in this figure represents the impulses sent out by the dial 63 and so represents the current in the relay 11. When this relay is energized, the output circuit of the vacuum tube 9 delivers audio-frequency current, represented 15 by the end portion of the curve B. When the relay is deenergized, no changes take place in the output circuit of the tube 9. This fact is represented by the absence of oscillations in the central part of B. When audio-frequency 20 changes are present in the output circuit of the tube 9, they cause the modulator tube 4 to change the character of the output of the generator tube 3, so that the energy impressed upon the antenna is of the character represented 25 by the two end portions of the curve C; that is, it is a radio-frequency carrier wave modulated at an audio frequency. When the modulator tube 4 is not influenced by the tube 9, because the relay 11 is de-energized, 30 the energy impressed upon the antenna is represented by the central part of the curve C; that is, it is an unmodulated carrier wave of radio frequency. The modulations of the carrier wave, therefore, occur in impulses.

35 40 When the energy is received upon the antenna 21 at the called station, if it is of the kind shown at the end portions of the curve C, it will produce in the output circuit of the first detector tube 23, a current properly represented by the end portions of the curve B. But if the energy received upon the antenna 21 corresponds to the central portion of the curve C, there will be a constant current in the output circuit of the detector tube 23 and 45 accordingly, no current in the secondary of transformer 24. The resulting current in the output circuit of the tube 23 is not correctly represented by the curve A, because to correctly represent it, the end portions of the 50 curve must be, not elevations, but depressions; for the current in the output of the final detector tube 23 is diminished during an impulse. The current in the circuit controlled by the relay 32 is correctly represented by the 55 curve A.

60 In Fig. 3, I have represented line conductors 100 and have shown the antennæ of several stations as inductively associated therewith. Either this method of transmitting, 65 or the transmission through space, usually

indicated by the conventional antenna shown in Figs. 1 and 2, may be used.

In Fig. 3 squares have been used to represent collections of apparatus which in Figs. 1 and 2 are shown in detail. The reference characters designating squares have each been chosen, by adding 100 to the reference character in Figs. 1 or 2 which designates a characteristic element in the collection of apparatus represented by that square. Three stations are shown in this figure, indicated respectively by D, E, and F. The station at which the apparatus designated by any reference character is to be found, will be indicated in the following description by affixing the letter designating the station to the numeral designating the apparatus.

The station D represents the dispatcher's station and is not equipped with any switching arrangement for changing the constants of the antennæ. The sending apparatus at the dispatcher's stations is permanently tuned to the frequency at which all the other stations are normally tuned to receive and the receiving apparatus at his station is permanently tuned to the frequency at which all the other stations are normally adjusted to send. A dial 63D controls the transmitting mechanism 109D so that the antenna 101D sends out a carrier wave modulated intermittently, the impulses of modulation corresponding to the impulses at the dial. This radiation is received upon each of the antennæ 121 and the receiving mechanisms 125E and 125F cause the corresponding selectors 184E and 184F to be stepped. Assuming that station E is the called station, the selector 184E will cause the bell 96E to ring. The operator at station E removes the telephone receiver 36E from its hook, with the result that conversation is possible between station D and station E. When the conversation is concluded, both operators hang up their receivers and the stations return to normal condition. 110

Assuming that the operator at station E wishes to call station F, he so manipulates the dial 63E as to cause the switching device 144E to change the characteristic wave lengths of the antennæ 101E and 121E. Before this change, the antenna 121E was tuned to receive the frequency sent out from the antenna 101D and the antenna 101E was tuned to send radiations that would correspond to the frequency for which antenna 121D was tuned. After this change, the frequencies characteristic of the antennæ 101E and 121E are interchanged, so that these antennæ are now tuned like the antennæ at station D having the same reference characters. The antennæ at station F are normally tuned as the antennæ at station E were before this change. The result of the change is that station E is ready to send and receive in the same way as the dispatcher's station and can also 125 130

communicate with station F, just as the dispatcher station would. The call is made by the dial 63E and the result of lifting the receivers 36E and 36F is the same as described in connection with the call from station D to station E.

If station F is calling station E, the operator begins by manipulating the switch 631, which has been added to this station to illustrate the provision of a separate, manually-operated circuit closer for controlling the changes in the antenna constants. The switch 631 actuates the switching device 144F for changing the constants of the sending antenna and the switching device 145F for changing the constants of the receiving antenna. Two switching devices are shown at station F, instead of the one switching device 144 which is shown at station E, in order to illustrate that the magnets 45, 47 and 49 may be controlled directly from a circuit closer, instead of, as illustrated in Fig. 2 having the magnet 44 control the other magnets.

While I have shown only one embodiment of my invention in the accompanying drawing, it is capable of other modifications and changes without departing from the spirit thereof. I desire, therefore, that only such limitations shall be placed thereon as are indicated in the prior art or in the appended claims.

I claim as my invention:

1. In a signalling system, a first station, a remote station, transmitting apparatus at said first station including a radio frequency current generator, means for modulating the radio frequency currents from said generator, means for controlling said modulations in accordance with a code comprising an evacuated tube, circuit connections electrically associated with said tube whereby said tube generates current of audio frequencies, circuit connections including a microphone connected to said tube, whereby said tube operates as an amplifier of the currents flowing from the microphone, means including a relay for switching said tube from said first to said second connection, a receiving device at said second station including a detector, means including circuit connections for translating said audio frequencies received at said receiver from said transmitting station, means including circuit connections for translating said code signals received from said transmitting station and means including a relay for associating either of said last two mentioned means with said receiving device.

2. In a radio system, a telephone transmitter, a telephone receiver, a selector switch, a carrier current modulator, a three element tube connected thereto, means including a relay for connecting said tube to said selector, means including said selector connected to said tube for transmitting code combinations

of impulses, means for switching said tube to said telephone transmitter and for simultaneously varying the characteristics of said tube whereby it acts as an amplifier of currents from said telephone transmitter, means including said circuit connections for radiating carrier current modulated by voice frequency, a receiver, a selector switch, said receiver being normally connected to said switch and operating in response to received code signals for operating said switch, and means responsive to a predetermined operation of said switch for switching said receiver to said telephone receiver whereby said telephone receiver operates in accordance with receiver voice currents.

In testimony whereof, I have hereunto subscribed my name this 20th day of October 1923.

CLARENCE A. BODDIE.
